UNITED STATES PATENT OFFICE.

WILLIAM EUTIN, OF CHICAGO, ILLINOIS.

WINDOW CONSTRUCTION.

Application filed May 2, 1925. Serial No. 27,535.

To all whom it may concern:

Be it known that I, WILLIAM EUTIN, a citizen of the United States, and a resident of Chicago, in the county of Cook and State 5 of Illinois, have invented certain new and useful Improvements in a Window Construction, of which the following is a full, clear, and exact description, such as will enable others skilled in the art to make and 10 use the same.

My present invention relates to windows wherein the usual window cords and counter-balance weights are employed for the purpose of controlling the operation 15 of the window sash. More particularly stated my present structure appertains to a special window frame and sash that permits the sash-cord to be readily assembled with the sash, the pulley and the counter- 20 weight without removing the sash from the frame. It is a further object of my invention to provide a novel manner of assembling the sash-cord with the counter-weight. Also it is an object of my invention 25 to provide a unique dividing partition in the weight-box of the window frame, and in this connection I have provided a novel construction for the weight-box whereby the weights may be readily han- 30 dled and dividing partition may be removed without the removal of the window sash.

I prefer to carry out my invention and accomplish the divers objects thereof in substantially the manner hereinafter fully de- 35 scribed and as more particularly pointed out in the claims. Reference will now be made to the accompanying drawings that form a portion of this specification, in which:—

40 Figure 1 is vertical longitudinal section of a window frame and weight box showing my invention applied thereto and the sash, etc., in complete assembly.

45 Figure 2 is a diagrammatic view of a section similar to Figure 1 showing in full lines the first step of assembling the window cord, and in dotted lines the second step of assembling.

50 Figure 3 is a horizontal section taken on line 3—3 of Figure 2.

55 Figure 4 is a fragmental detail of a portion of the weight, and the opening for access thereto and for the removal of the dividing partition.

55 The drawings illustrate a typical or preferred embodiment of my invention, and

throughout the figures I have employed similar reference characters to designate like parts wherever the same appear.

As seen the side of the window provides the usual weight-box 5 one of the walls of which has a strip 6 mortised therein to separate and guide the upper and lower sashes 7 and 8 respectively. The interior of the weight-box is divided by a novel partition 60 in the form of upper and lower strips of flat rigid material 9 and 10 that have their adjacent ends spaced apart and joined by means of a flexible connecting piece 11 of canvas, leather, or the like in strip form and said partition hangs pendent upon a hook 12 mounted in the upper portion of the box so that it may be readily lifted off the hook and removed from the box when desired, as will hereinafter appear.

70 The usual pulley 13 and its holder 14 are mounted in the upper portion of the frame to receive the sash cord 15.

75 As is well-known, it is usual when replacing a broken sash-cord to remove a 80 guide strip 6 or the molding strip 24 and disassemble the sash from the frame, which is a laborious undertaking and necessitates leaving the window open during the work 85 of replacing the cord which in inclement weather is inconvenient and chills the room or apartment where the window is located. In order to overcome this inherent objection to the well-known construction I have provided a passageway or opening 16 in the 90 frame below the pulley. The usual cord groove 17 extends longitudinally down from the top of the sash in the side edge thereof and at its lower end I have provided a lateral passageway or aperture 18 that leads 95 obliquely (Fig. 3) to an enlarged recess or pocket 19 in the inside face of the sash, which pocket is closed by a countersunk plate 20. The closure plate 20 may be readily removed from the inner side of the 100 window and the sash moved to a position where the passageways or apertures 16 and 18 are in registry as shown in full lines in Fig. 2 and in transverse section in Fig. 3 whereupon a new sash cord may be inserted 105 through said apertures with a short length depending in the weight box. Upon lowering the sash until its top edge is below passageway 16 the cord will have been seated in the edge groove 17 and the remaining 110 portion is then pulled out of the box 5 and reinserted therein by passing its end over

the pulley 13 as illustrated in dotted lines, Fig. 2. Sufficient cord is now pulled upwardly through groove 17, passageway 18 and the pocket 19 until the inner lower end 5 is adjacent the bottom of the box 5. The inner lower end of the cord may now be secured to the counterweight 21, after which the cord is measured the desired length and cut and knotted with the knot 22 disposed in 10 the pocket 19 after which the closure plate 20 is secured in position and the sash is again ready for use.

At a convenient place in the frame a preferably L-shaped opening is made, the vertical member 23 of which opening is located 15 in the guide of the frame between the strip 6 and the inside retainer strip 24, and the lateral member 25 of this opening extends behind the retainer strip 24 so as to be covered thereby and obscured from view. This 20 opening permits the ready securing of the cord 15 to the counter-weight, and on account of its shape the opening permits the workman, after removing the strip 24, to 25 insert his hand through the same and perform his work more conveniently. When the dividing partition is to be removed it is lifted off the hook 12 and may be partly collapsed by lowering the section 9 slightly 30 to loop the flexible section 11 and due to the fact that the sections are short they may each be tilted slightly and removed through the lateral member 25 of the L-shaped opening. In order to exclude dust and other 35 matter from access to the box through this L-shaped opening I prefer to employ a closure plate 26 that is counter-sunk in the guideway one edge of which plate meets the adjacent edge of the retainer strip 24 and together therewith completely 40 closes and covers the opening.

From the foregoing it will be seen I have provided a very novel window frame and sash structure that permits of the replacing 45 of a window cord without removing the sash from the frame and liability of "losing" the cord by having it drop back into the weight box is reduced to a minimum. It will be obvious that divers changes in the precise 50 structure herein disclosed may be made without departing from the principles of my invention. I desire it understood that all such changes, or any refinements of my invention, are fully contemplated as coming 55 within the scope of the appended claims.

What I claim as new is:—

1. A window construction comprising a frame having a lateral aperture, and a sash co-operating therewith and having a lateral

aperture, said apertures adapted to be 60 brought into registry whereby a sash cord may be inserted therethrough and into the weight-box of the frame.

2. A window construction comprising a frame having a lateral aperture, and a sash 65 co-operating therewith, said sash having a lateral aperture extended inwardly from an edge adjacent said frame and a pocket at the inner end of said aperture to which access is readily had from the inside of the 70 window, whereby when said apertures are brought into registry a sash may be inserted through the same and into the weight-box of the frame.

3. A window construction comprising a 75 frame, a sash slidable therein, said frame and sash provided each with an aperture adapted to be brought in registry one of said apertures opening into the weight-box of the frame and the other aperture being 80 accessible from the inside of the window whereby a sash cord may be inserted through the alined apertures and into the weight-box of the frame without removing 85 the sash from said frame.

4. A window construction comprising a frame having a weight-box, a partition dividing said box formed from two rigid sections and a flexible section connecting said rigid sections, and means for supporting 90 said partition within said box, said box having an elongated aperture in one of its walls through which said partition may be removed.

5. A window construction comprising a 95 frame having a weight-box having an L-shaped opening leading into the same, a collapsible partition dividing said weight-box longitudinally and removable through said opening, and a sash movable in said 100 frame, said sash and frame provided with transverse apertures and adapted to be brought into registry to provide a passageway from the inside of the sash to the interior of the box whereby a sash cord may be inserted into said box without removing 105 the sash from the frame.

6. A window frame, a sash slidable therein, and means in the frame and sash adapted to be brought into co-ordination 110 with each other whereby a sash-cord may be inserted into the weight-box of said frame without the removal of the sash.

Signed at Chicago, in the county of Cook and State of Illinois, this 22nd day of April, 115 1925.

WILLIAM EUTIN.
